UNITED STATES PATENT OFFICE.

WILLIAM MANSON PHILLIPS, OF FERRIS, TEXAS.

QUILTING-FRAME.

SPECIFICATION forming part of Letters Patent No. 626,928, dated June 13, 1899.

Application filed June 27, 1898. Serial No. 684,613. (No model.)

To all whom it may concern:

Be it known that I, WILLIAM MANSON PHILLIPS, a citizen of the United States, residing at Ferris, in the county of Ellis and State of Texas, have invented a new and useful Quilting-Frame, of which the following is a specification.

My invention relates to quilting-frames, and has for its object to provide a simple and efficient construction and arrangement of parts, including a cover adapted for use to protect the quilt upon the frame from accumulations of dust.

Further objects and advantages of this invention will appear in the following description, and the novel features thereof will be particularly pointed out in the appended claims.

In the drawings, Figure 1 is a perspective view of a quilting apparatus constructed in accordance with my invention, the cover being shown in its folded or inoperative position. Fig. 2 is a similar view showing the cover in its operative position. Fig. 3 is an edge view of the quilting-frame as seen when folded.

Similar numerals of reference indicate corresponding parts in all the figures of the drawings.

1 designates intersecting end bars, which are pivotally connected for folding and which at their upper ends support the side bars or rollers 2 and 3, between which the quilt is stretched. The pivots by which the end bars are connected preferably consist of reduced terminals of a longitudinal brace 4, and fulcrumed upon extensions of these reduced terminals are the end arms 5 of a cover-frame, said arms being provided at their free ends with bearings, in which are mounted the reduced terminals or trunnions of a cover-roller 6. Attached to said cover-roller is a flexible covering-sheet 7, of any suitable material, adapted to be spread over a quilt when the frame is not in use or when the quilter is not occupied in quilting. The end arms of the cover-frame are notched, as shown at 8, to receive the extended terminals or trunnions of the side or quilting rollers, said extended trunnions forming stops to limit the swinging movement of the cover-frame and the notches being designed to allow the device to fold

compactly when not in use. Preferably only one terminal of each quilt-roller is extended to form a stop for the cover-frame, the relatively opposite trunnions of said quilt-rollers being extended for this purpose, whereby a stop is arranged in the path of each arm of the cover-frame, one stop serving to prevent excessive movement of the cover-frame in one direction while the other stop performs a similar function in connection with the movement of the cover-frame in the opposite direction.

In order to limit the spreading movement of the end bars of the quilting-frame, particularly during the application of batting, I employ flexible connections 9, such as cords, attached at one end to the upper end of one of the pivotally-connected end bars and provided at the other end with a loop 10, of suitable material, for engagement with the upper extremity of the other end bar, those end bars which are engaged by the loops being provided with suitable seats or notches 11 to prevent the accidental disengagement of the loops therefrom.

When it is desired to leave a quilt upon the frame, the latter being extended, the cover-frame, which normally occupies a vertical position out of the way of the operator, should be moved to a position approximately parallel with one of the members of the quilt-frame or over one of the side bars or rollers, as indicated in Fig. 2, and the cover-sheet should then be extended across the frame. When it is desired to use the quilting-frame or to resume the quilting operation, the cover-sheet should be rolled upon the drum provided for that purpose and the arms arranged in a vertical position, whereby the cover-roller is positioned above the plane of the quilt, and hence out of the way of the operator.

When the quilting-frame is folded, as indicated in Fig. 3, the flexible holding devices or connections between the members of the frame may be wound around the side bars or rollers with the terminal loops engaged with the seats provided for that purpose, and the cover-sheet may be similarly wrapped around the side bars or rollers and their contents.

Various changes in the form, proportion, and the minor details of construction may be

resorted to without departing from the spirit or sacrificing any of the advantages of this invention.

Having described my invention, what I claim is—

- 5 1. The combination with a quilting-frame, having side bars or rollers, of an auxiliary cover-roller, a pivotal frame for the cover-roller, mounted upon the supporting-frame of said side bars or rollers, and capable of swinging movement to arrange said cover-roller adjacent to either side roller, and a covering-sheet attached to the cover-roller, substantially as specified.
- 15 2. In a quilting-frame, the combination with pivotally-connected end bars and connecting side bars or quilt-rollers, of end arms mounted coaxially with said end bars, a cover-roller mounted in bearings at the free ends of said arms, and a covering-sheet attached to said cover-roller, substantially as specified.
- 20 3. The combination with a quilting-frame having pivotally-connected end bars, and side bars or quilt-rollers mounted in bearings in said end bars, of a cover having end arms fulcrumed coaxially with the said end bars, and of a length greater than the upper arms of
- 25

said end bars, and a cover-roller mounted in bearings in the end arms and carrying a covering-sheet, stops being carried respectively by the upper arms of the end bars in the path of said end arms, to limit the swinging movement of the latter, substantially as specified. 30

4. The combination with a quilting-frame having pivotally-connected end bars, and side bars or quilt-rollers mounted in bearings in said end bars, of a cover having end arms fulcrumed coaxially with the said end bars, and of a length greater than the upper arms of said end bars, and a cover-roller mounted in bearings in the end arms and carrying a covering-sheet, the side bars or quilt-rollers being terminally extended beyond the end bars to form stops in the path of said end arms to limit the swinging movement of the latter, 45 substantially as specified.

In testimony that I claim the foregoing as my own I have hereto affixed my signature in the presence of two witnesses.

WILLIAM MANSON PHILLIPS.
